UNITED STATES PATENT OFFICE.

JOHN HUMPHREYS, OF CASPER, WYOMING.

COMBINATION TOOL.

Application filed May 2, 1923. Serial No. 636,120.

To all whom it may concern:

Be it known that I, JOHN HUMPHREYS, a citizen of the United States, residing at Casper, in the county of Natrona and State 5 of Wyoming, have invented certain new and useful Improvements in Combination Tools, of which the following is a specification, reference being had to the accompanying drawings.

10 This invention relates to combination tools and more particularly to a device of this character especially intended for use in splicing wire and in serving pipe, tool handles and the like with wire.

15 An important object of the invention is to provide a device of this character which is extremely simple in its construction and arrangement, which may be very cheaply produced and which will be durable and 20 efficient in service.

A further object of the invention is to provide a device of this character having means for holding wire while serving a tool or the like, the holding means being such 25 that the tension of the wire may be readily regulated.

30 A further object of the invention is to provide a tool of this character having means for holding and guiding two wires while splicing the same.

These and other objects I attain by the construction shown in the accompanying drawings, wherein for the purpose of illustration is shown a preferred embodiment 35 of my invention and wherein:

Figure 1 is a perspective view of a combination tool constructed in accordance with my invention;

40 Figure 2 is a side elevation showing one side of the head of the tool;

Figure 3 is a section on the line 3-3 of Figure 2;

Figure 4 is a perspective view showing the tool in use for serving;

45 Figure 5 is a similar view showing the tool in use for splicing;

Figure 6 is a side elevation of the opposite side of the tool head from that shown in Figure 2, parts being broken away; and

50 Figure 7 is a section on the line 7-7 of Figure 2.

Referring now more particularly to the drawings, the numerals 10 and 11 indicate tool sections, the tool section 10 being provided with a pivot 12 and the section 11 having a flanged extension 13 at one side

thereof rotatably engaging the pivot. This flange has a sliding engagement against the side face of the section 10, as at 14, with its inner face and accordingly serves as a shear or wire cutter. The faces of the sections 10 and 11 may be brought into engagement with one another and that portion of the faces next adjacent the pivotal connection of the sections forms a plier face, indicated at 15, and the face of one of the sections may be provided with transverse holding grooves 16 at this point, if so desired. Adjacent their rear ends the adjacent faces of the sections 10 and 11 are provided with transversely extending concave slots 17, the faces of which are serrated and which combine to form jaws for holding round articles such as pipe or the like.

The rear ends of the members 10 and 11 are reduced and form handle portions 10^a and 11^a, the extremity of the handle portion 10^a being bent toward the handle portion 11^a, as indicated at 18, to provide a flange.

The adjacent face of the handle portion 11^a has pivoted thereto, as at 19, a hook member 20 interchangeably engageable in openings 21 formed in this flange for a purpose presently to appear. The flange is provided with a further opening 22 for

guiding wire while the device is being employed as a serving tool. The end portion of the handle 11^a is flattened to form a screw driver point, as indicated at 23. At the opposite side of the pivot point from the handle members the member 10 is offset, as indicated at 24, and formed to provide a hook the end of which is provided with a claw 25.

The offsetting of the section 10 is toward that side thereof which is abutted by the section 11, and that face of the hook next adjacent the section 11 is provided with an outstanding flange 26 overlying the section 10 in spaced relation thereto and combining therewith to form a guiding channel 27.

Through the section 10 an opening 28 is formed connecting the face of the section 10 next adjacent the section 11 with the interior of the hook 24. The sections 10 and 11 are of the same width and the section 11 is provided upon the pivoted end thereof and at the opposite side thereof from the flange 13 with an outstanding lug 29, the face of which next adjacent the hook 24 has formed therein a V groove 30. The outer face of the hook 24 is preferably provided

In employing the device for serving a tool, hose or the like, a wire is passed through the opening 22 of the flange 18 and between the adjacent faces of the sections 10 and 11, which may hereinafter be referred to as jaws, and through the opening 28. One end of this wire is then secured to the member to be served in any suitable manner and this member is engaged in the concavity of the hook 24. The hook 20 of the handle member 11^a is then engaged in one of the openings 21, the openings selected being that which will cause the jaw faces to come together upon the wire W with sufficient force to necessitate a desired tension being applied to the wire to draw the same through these jaw faces. The tool is then rotated about the member to be served in the direction of the arrow in Figure 4. Attention is directed to the fact that during this operation the tension of the wire tends to maintain the member being served in position in the concavity of the hook and accordingly the operator's attention may be entirely given to observation of the serving to determine that this is being properly accomplished.

When the device is employed for splicing the adjacent ends of two wires, the wires are overlapped and maintained in parallel position by engaging a shear or pliers therewith, as indicated in dotted lines in Figure 5 at P. With the wires so held the short end S of one wire is bent upwardly at right angles to the remaining wire and this wire is then engaged in the channel 27 formed by the jaw section 10 and the flange 26. The up-bent end S is then engaged in the groove 30 of the lug 29 and the tool rotated about the wire within the channel 27 as a center and in the direction of the arrow in Figure 5. This rotation will cause the short end S to be wound about the wire within the channel, thus forming one-half of a Westinghouse splice. By similarly treating the short end S' of the other wire the splice is completed.

It is believed that the remaining usages of the tool will be obvious. It will be readily seen that the same may be employed as a tack puller, screw driver, hammer, pipe wrench or cutting pliers, as may be desired. It will further be seen that these devices have been so combined as to provide a very compact tool and one which may be very cheaply produced. It will, of course, be understood that certain changes and modifications are possible in the structure thereof and I accordingly do not limit myself to this specific arrangement hereinbefore set forth except as hereinafter claimed.

I claim:—

1. In a device of the type described, two pivotally connected members formed adjacent their pivot to provide clamping jaws, one of said members being provided with

an extension forming a hook, and having an opening extending therethrough from the face thereof next adjacent the other member to the concave face of the hook.

2. In a device of the type described, a member having a flat face and provided at one end of the flat face with an offset portion formed to provide a hook, said member having an opening extending therethrough from the flat face thereof to the concave face of the hook, and means coacting with the first named member for frictionally engaging a wire extended through said opening to the flat face thereof.

3. A tool of the type described, including a member having a guide channel and a portion opposing and spaced from said guide channel having a slot therein disposed at right angles to the guide channel.

4. In a device of the type described, a member having a flat face and provided at one end of the flat face with an offset portion formed to provide a hook and having an opening extending therethrough from the flat face thereof to the concave face of the hook, and means coacting with the first-named member for frictionally engaging a wire extended through said opening to the flat face thereof, said member having an extension at the opposite end thereof from said hook, said extension having a guide opening, a plane common to the guide opening and the first-named opening intersecting the flat face of the member.

5. In a device of the type described, two pivotally connected members formed adjacent their pivot to provide clamping jaws, one of said members being provided with an extension forming a hook, and having an opening extending therethrough from the face thereof next adjacent the other member to the concave face of the hook, a flange formed on said hook and directed toward the other member, said flange overlying the member provided with a hook in spaced relation thereto to provide a guide channel and a lug formed on the other of said members and having a notch disposed at substantially right angles to said channel.

6. In a device of the type described, two pivotally connected members formed adjacent their pivot to provide clamping jaws, one of said members being provided with an extension forming a hook, and having an opening extending therethrough from the face thereof next adjacent the other member to the concave face of the hook, the ends of said members remote from the pivot being extended to form handles, one of said members being provided with a flange directed toward the other of the members, the other of said members having a pivotal hook selectively engageable in openings formed in said flange.

7. In a device of the type described, two

5 pivotally connected members formed adjacent their pivot to provide clamping jaws, one of said members being provided with an extension forming a hook, and having
10 an opening extending therethrough from the face thereof next adjacent the other member to the concave face of the hook, the free end of said hook being formed to provide a claw.
15 8. In a device of the type described, two pivotally connected members formed adjacent their pivot to provide clamping jaws,

one of said members being provided with an extension forming a hook, and having an opening extending therethrough from 15 the face thereof next adjacent the other member to the concave face of the hook, one of said members being provided with a flange slidably engaging the side of the jaw of the other of the members and combining therewith to provide a shear.
20

In testimony whereof I hereunto affix my signature.

JOHN HUMPHREYS.
